US00D830345S

(12) **United States Design Patent** (10) Patent No.: **US D830,345 S**
Cai (45) Date of Patent: **** Oct. 9, 2018**

(54) **EARPHONE**

(71) Applicant: **Hejin Cai**, Guangdong (CN)
(72) Inventor: **Hejin Cai**, Guangdong (CN)
(**) Term: **15 Years**
(21) Appl. No.: **29/645,503**
(22) Filed: **Apr. 26, 2018**
(51) LOC (11) Cl. **14-01**
(52) U.S. Cl.
USPC **D14/223**

(58) **Field of Classification Search**

(57) **CLAIM**

The ornamental design for an earphone, as shown and described.

DESCRIPTION

FIG. 1 is a perspective view of an earphone showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line portions of the earphone in the drawings represent unclaimed portions of the claimed design and form no part thereof.

1 Claim, 5 Drawing Sheets
